(57) **CLAIM**

The ornamental design for a pacifier shield accessory, as shown and described.

DESCRIPTION

FIG. 1 is a top, front, right perspective view of a pacifier shield accessory, showing my new design;

FIG. 2 is a bottom, front, left perspective view thereof;

FIG. 3 is front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is a cross-sectional elevation view of the pacifier shield accessory, taken in the direction of line 9-9 of FIG. 3; and,

FIG. 10 is a top, front, right perspective view of the pacifier shield accessory, shown interconnected to a pacifier in a condition of use for clarity of disclosure.

In the drawings, the equal-length broken lines depict portions of the pacifier shield accessory that form no part of the claimed design. The dash-dot-dash broken lines define the bounds of the claim. The broken line showing of a pacifier in FIG. 10 depicts environmental subject matter only and forms no part of the claimed design. All broken lines form no part of the claimed design.
